FIG. 2. Inventor
Henry Salisbury

By *Frederick J. Hayes*

Attorney

UNITED STATES PATENT OFFICE.

HENRY SALISBURY, OF BROOKLYN, NEW YORK.

SASH-FASTENER.

No. 842,340.

Specification of Letters Patent.

Patented Jan. 29, 1907.

Application filed September 8, 1905. Serial No. 277,527.

To all whom it may concern:

Be it known that I, HENRY SALISBURY, a citizen of the United States, residing at Brooklyn, in the county of Kings, State of New York, have invented certain new and useful Improvements in Sash-Fasteners; and I do hereby declare the following to be a full, clear, and exact description of the invention, such as will enable others skilled in the art to which it appertains to make and use the same.

This invention relates to sash-fasteners.

One object of the invention is to provide an exceedingly simple, inexpensive, durable, and efficient sash-fastener.

Another object of the invention resides in the provision of a sash-fastener embodying such characteristics that the windows may be locked either in their open or closed positions and whereby both windows may be moved simultaneously upon movement of one of them in their open position.

A still further object of the invention is to provide a sash-fastener of such nature that the window may be positively locked against opening from the outside and embodying the still further feature of preventing rattling of the windows when closed.

With these and other objects in view the present invention consists in the combination and arrangement of parts, as will be hereinafter more fully described, shown in the accompanying drawings, and particularly pointed out in the appended claim, it being understood that changes in the form, proportion, size, and minor details may be made within the scope of the claim without departing from the spirit or sacrificing any of the advantages of the invention.

In the drawings, Figure 1 is a sectional view of a portion of and an elevation of a window-frame, illustrating upper and lower sashes with my fasteners arranged thereon. Fig. 2 is an elevation of the structure shown in Fig. 1.

Referring more particularly to the drawings, the reference character 1' designates the lower sash, and 2' the upper sash. These sashes may be of any ordinary form of construction.

Mounted upon the top rail 23 of the lower sash adjacent each side of the latter is a fastening-plate 21, provided with a depending flange 22, having a perforation through which the retaining-screws are passed. This 55 plate 21 is provided upon its upper face with ears 24 for the reception therebetween of the locking-bar 26, held by the pivot 24' and whose opposite end is provided with a screw-threaded eye 27, in which is fitted the screw-threaded shank 28 of the bolt 29, whose extremity is adapted to engage in the screw-threaded perforations of a plate 14', secured to the front face of the said rails of the upper sash 2', there being perforations 29' formed in 65 said rails in alinement with the perforation formed in the plate 14'. This last-mentioned plate is preferably provided with a series of integral horizontal sleeves in which the perforations above referred to are formed. 70

When it is desired to unlock the windows—that is, disengage the shank 28 of the bolt 29 from the perforations of the plate 14' of the upper sash 2'—it is simply necessary to manipulate the locking-bolt 29 accordingly 75 and then turn the lock-bar 26 downwardly upon the top face of the upper rail 23 of the lower sash. By reason of the pivotal mounting of the lock-bar 26 it is possible that the latter might interfere with the proper raising 80 and lowering of the respective sashes, and I therefore provide U-shaped supports 30', whose shanks 31 are screwed through the plates 21 into the upper rail of the lower sash 1'. These supports 30' receive the locking-bar 26 when the windows are unfastened and prevent sidewise or other movement of the locking-bar 26 and its bolt 29, as well understood.

It is manifest that only one fastener at one 90 end of a window will answer the purpose herein stated, and it is apparent that whether one or two fasteners be employed the insertion of an instrument between the meeting rails of the respective sashes could not in any 95 way manipulate the bolt 29 so as to disengage its shank from its locked position.

What is claimed is—

The combination with a window, of a plate having a threaded passage therein secured to 100

one of the sashes, a plate secured to the other sash, spaced ears carried by the second plate, a bar pivoted between the ears and having an eye therein, a screw engaged in the eye, 5 said bar being moved upon its pivot, to bring the bar into and out of position to enter the opening of the first-named plate, and a yoke arranged to receive the bar therein

when out of position for engagement with the screw in said opening.

In testimony whereof I affix my signature in presence of two witnesses.

HENRY SALISBURY.
